United States Patent Office

Des. 178,871
Patented Oct. 2, 1956

178,871

CASING FOR A THERMOSTAT OR THE LIKE

Rooney W. Davis, Webster Groves, Mo., assignor to Missouri Automatic Control Corporation, St. Louis, Mo., a corporation of Missouri

Application July 15, 1955, Serial No. 36,982

Term of patent 14 years
(Cl. D52—7)

Fig. 1

Fig. 3

Fig. 2

Fig. 1 is a front elevation of a casing for a thermostat showing my new design;
Fig. 2 is a bottom view thereof; and
Fig. 3 is an end elevation thereof.
I claim:
The ornamental design for a casing for a thermostat or the like, substantially as shown.
